COMBINED CLAMP AND LIFTER FOR FRUIT PACKING TUBS

Filed Sept. 16, 1929 2 Sheets-Sheet 2

Inventor,
Samuel H. Sheller
By *Frank Pauling* *Atty*

UNITED STATES PATENT OFFICE

SAMUEL H. SHELTER, OF MARION, PENNSYLVANIA

COMBINED CLAMP AND LIFTER FOR FRUIT PACKING TUBS

Application filed September 16, 1929. Serial No. 392,886.

Prior to my invention described in another application executed of even date herewith, the method commonly employed for packing peaches, apples or other fruit in baskets, has been to use a facing former to support the paper liner for the basket, the latter having first been inserted in a metal tub or shell and placed in an inverted position on the said facing former. After filling the liner, the metal tub or shell has been removed, following which step, the fruit basket has been placed in inverted arrangement over the filled paper liner, following which the basket, liner, fruit, and facing former have been turned right side up, a special reversible clamp being employed for that purpose. The facing former has next been removed and the usual cap or cover for the basket has been fastened to the basket.

The improved method set forth in my aforesaid application greatly simplifies and shortens the packing operation by employing the fruit basket cover itself as the facing former after equipping said cover or top with a novel internal cap which also co-operates with the paper liner in an improved manner to protect the fruit from being bruised.

According to my improved method, set forth in the aforesaid application, the utilization of the basket cover or cap as the facing former, enables the fruit basket, when telescoped over the filled liner, to be directly connected to the cover or top so that when the basket is reversed or set right side up, it constitutes a packed, completely finished, basket.

The present invention has for its object the provision of a tub or shell, such as has heretofore been used, having improved means for engaging the basket top or cover employed in practicing my improved method set forth in the aforesaid application, whereby the filled paper liner, basket cover or cap, and tub, may be transported as a unit to a suitable point and the tub then disconnected from the cover or top so that it may be used at once in connection with another liner and basket cover or top and enabling the person who telescopes the fruit basket over the previously filled liner to attach that basket to the top which has been used as a facing former.

The improved means on the tub for engaging the cover or top of the fruit basket, is preferably in the form of combined elevating handles and clamps provided at one end with means to engage the projecting ends of the fastening slat of the cover or top and at the other end, with handles which are arranged to be readily grasped by the operator. The handles are preferably spring-actuated to prevent them from accidentally disengaging from the ends of the fastening slat of the cover.

One embodiment of the invention is hereinafter described and shown in the accompanying drawings but it will be understood, however, that unless specified in the claims, the invention is not limited to the particular clamp and handle shown and described.

In the accompanying drawings:

Figure 1 is a side elevation of a tub or shell provided with the present improvements, in position on a basket cover or top used as a facing former and locked thereto;

Fig. 2 is a similar view, taken at right angles to Fig. 1; and

Fig. 3 is a side elevation illustrating both the manner of applying the tub to the liner and top or cover and detaching it therefrom.

The metal tub or shell 1 is open at its top and bottom, being of the usual truncated conical form employed in the fruit basket industry.

My improvements reside in the guides 2 and the combined handles and clamps 3 which will presently be explained.

The paper liner 4 may be of any preferred construction, said liner being first inserted in the tub or shell 1.

The practice heretofore has been to use a special facing former on which rests the liner 4.

In accordance with the improvements set forth in my aforesaid application, I dispense with the ordinary facing former and use as a facing former, the ordinary slatted cover or top 5 for the wooden fruit basket top having one of its slats provided with projecting ends 6, in accordance with approved practice.

I have illustrated herein an improved cap

- 7 contained within the cover or top 5, full disclosure of which is made in my aforesaid application. The cap 7 is provided with a peripheral flange 7' extending all the way around and interposed between the fruit 8 and the rim of the cover 5 as also projecting into the liner 4 so that the fruit can neither press against the cover 5 nor the fruit basket (not shown).
- 10 The guides 2 are in the form of metal straps having springy bent ends 2' arranged to engage the rim of the cap 5 and to center the tub 1 thereon so that it will not become laterally displaced. Certain of these straps 15 may extend substantially the height of the tub or shell 1 for the attachment of the brackets 9 which mount the combined handles and clamps 3. The straps may be attached to the tub by rivets.
- 20 The combined handles and clamps 3 are of relatively rigid strap metal stock having clamping loops 10 which are adapted to receive the ends 6. The other ends of the clamps have handles 11 of open construction. The clamps are pivoted to the brackets 9 in any suitable manner, as by bolts 12.
- 25 By preference, suitable spring means are employed to so actuate the combined handles and clamps that their lower parts will be 30 pressed inwardly toward the tub or shell 1 and thus will be prevented from accidentally becoming disengaged from the projecting ends 6. The springs also normally position the handles 11 outwardly from the tub as 35 shown in Fig. 1, so that they can be conveniently grasped by the hands of the operator. As shown, the springs appear at 13, being wrapped around the bolt 12 and having their ends engaged with the brackets 9 and the 40 handles and clamps 3.
- Assuming that the liner 4 has been placed upon the basket cover or top 5, or, said liner has first been inserted in the tub 1, after the 45 facing layer of fruit has been placed on said cover, the handles 11 are grasped as shown in Fig. 3, to insert the clamps 10 and the said clamps 10 are then engaged with the ends 6, as shown in Figs. 1 and 2. The liner 4 may then be filled with fruit in the usual 50 manner.
- When the liner 4 is completely filled, the operator grasps the handles 11 with an elevating action, without pressing them toward the tub 1 and thus can readily transport the 55 tub, liner, fruit and top 5, to a suitable table or location where an operator will be ready to place the fruit basket over the filled liner and connect it to the cover 5. Having thus transported the filled liner and cover, the 60 operator presses the handles 11 toward the tub, thereby disengaging the clamps 10 from the ends 6 so that the tub can be used on another basket cover and in connection with another liner.
- 65 What I claim is:

1. The combination with a tub or shell for use in packing fruit, and a fruit support, of combined clamps and lifters carried by the tub which clamp the fruit support to the tub while serving as sustaining and carrying devices by which the fruit and fruit support may be carried from place to place. 70
2. The combination with a tub or shell for use in packing fruit, and a fruit support, of combined clamps and lifters carried by the tub which clamp the fruit support to the tub while serving as sustaining and carrying devices by which the fruit and fruit support may be carried from place to place, comprising rockably mounted devices provided with fruit-support engaging means at their lower ends and with operating handles at their upper ends. 75
3. The combination with a tub or shell for use in packing fruit, of combined clamps and lifters carried thereby adapted to engage the support for the fruit and to clamp it to the tub, comprising rockably mounted devices provided with fruit-support engaging means at their lower ends and with operating handles at their upper ends, and spring means co-operating with said combined clamps and lifters and serving to hold the clamps in engagement with the fruit support when the tub is being suspended and carried by the 80 combined clamps and lifters. 90
4. The combination with a fruit basket cover or top adapted to be used as a facing former or support for the fruit, of a tub or shell, and combined lifters and clamps carried by said tub and adapted to engage the said fruit basket cover or top when the tub surmounts said cover or top and clamp the cover to the top and also serving, when thus engaged with the cover, as suspending and carrying lifters by which the tub, fruit, and cover or top may be transported with the cover clamped to the tub. 100
5. The combination with a fruit basket cover or top having projecting parts, of a tub or shell, combined lifters and clamps movably mounted on said tub or shell and provided with loops adapted to receive the projecting parts on the cover or top when the latter is used as a facing former or support for fruit, thereby to lock the tub to said cover or top, and also having means by which they may be manually operated. 110
6. The combination with a fruit basket cover or top having projecting parts, of a tub or shell, combined lifters and clamps movably mounted on said tub or shell and provided with loops adapted to receive the projecting parts on the cover or top when the latter is used as a facing former or support for fruit, thereby to lock the tub to said cover or top, and also having means by which they may be manually operated, and spring means co-operating with said combined lifters and clamps which tend to hold the loops in en- 120
- 130

gagement with the projecting parts of the cover or top.

7. The combination with a tub or shell adapted for use in a fruit packing basket operation, of fixed guides secured thereto having ends which freely project beyond the end of said tub or shell and are adapted to prevent lateral displacement of the facing former which is intended to be surmounted by said tub or shell during the packing operation.

8. The combination with a fruit basket cover or top adapted for use as a facing former in a fruit basket packing operation, of a tub or shell having guides secured thereto provided with ends of springy construction which freely project beyond the end of said tub or shell and extend crosswise of the edge of the facing former to serve as retainers, preventing lateral displacement of said facing former to maintain the tub in superposed relation to the cover or top.

9. The combination with a fruit basket cover or top adapted for use as a facing former in a fruit basket packing operation, of a tub or shell having guides adapted to extend crosswise of the edge of the said cover or top to maintain the tub in superposed relation to the cover or top and prevent relative lateral displacement of the tub and facing former, and combined lifters and clamps carried by the said tub which are adapted to releasably engage the cover or top to lock the tub thereto.

35 In testimony whereof I affix my signature.
SAMUEL H. SHELLER.
